(57) **CLAIM**

We claim the ornamental design for a filtration header, as shown and described.

DESCRIPTION

FIG. 1 is a plan view from front;
FIG. 2 is a plan view from back;
FIG. 3 is a plan view from left side;
FIG. 4 is a plan view from right side;
FIG. 5 is a plan view from top;
Fig. 6 is a plan view from bottom;
FIG. 7 is an isometric view from top right;
FIG. 8 is an isometric view from bottom right;
FIG. 9 is an isometric view from top left;
FIG. 10 is an isometric view from bottom left;
FIG. 11 is a top view; and,
FIG. 12 is a cross-sectional view taken along line A-A in FIG. 11.
